ATTORNEY

UNITED STATES PATENT OFFICE.

OLE H. MELLUM, OF UNION, NORTH DAKOTA.

COMBINATION PLIERS AND WRENCH.

1,294,689.

Specification of Letters Patent. Patented Feb. 18, 1919.

Application filed June 21, 1918. Serial No. 241,244.

To all whom it may concern:

Be it known that I, OLE H. MELLUM, a citizen of the United States, residing at Union, in the county of Cavalier and State 5 of North Dakota, have invented certain new and useful Improvements in Combination Pliers and Wrenches, of which the following is a specification.

This invention is a combination plier and 10 wrench and has for its principal object the production of a structure formed of a plurality of jaws which may be used for either the purposes of a wrench or pliers.

Another object of this invention is the 15 production of a combination plier and wrench wherein one jaw coöperates with the remaining jaw when the device is operated either as a wrench or plier.

Another object of this invention is the 20 production of a combination plier and wrench, wherein a primary jaw coöperates with the secondary jaw for the purposes of a wrench, while a plier jaw is pivoted upon the body of the secondary jaw and engages 25 the primary jaw for the purposes of a pair of pliers.

Broadly stated, this invention consists of a primary jaw and a secondary jaw having 30 enlarged bodies pivotally connected together, handle portions extending from said bodies, said primary jaw having teeth upon the outer edge thereof, a plier jaw having a body portion pivotally mounted upon the body portion of the secondary jaw, said 35 plier jaw having teeth thereon engaging the teeth of the primary jaw thus permitting the device to be used either as a pair of pliers or as a wrench.

One practical form of construction and 40 assembly of the present invention will be hereinafter described and is illustrated in the accompanying drawing, in which

Figure 1 is a side elevation of a combination plier and wrench.

Fig. 2 is a section taken on the line 2—2 of Fig. 1.

Fig. 3 is a section taken on the line 3—3 of Fig. 1, and

Fig. 4 is a side elevation of the combination plier and wrench showing the wrench jaws separated and in condition to receive a nut therebetween.

In the preferred embodiment of the present invention about to be described, it will 55 be seen that the wrench portion of the tool

comprises a primary jaw 5 and the auxiliary jaw 6. The primary jaw 5 has a thickened body 7 extending therefrom, while the auxiliary jaw 6 has a thickened body 8 extending therefrom. The bodies 7 and 8 bear 60 upon each other and as they are comparatively broad will reduce friction and they are further pivotally connected together by the bolt 9 extending therethrough which carries the nut 10, as shown in Fig. 3. 65 The handles 11 and 12 extend from the bodies 7 and 8 for a considerable distance and thus it will be seen that efficient operating means are provided for moving the jaws away from each other or toward each 70 other as occasion may require. As shown in Fig. 1, the jaws are in a closed condition, although it is obvious that in use, the jaws are adapted to be swung apart, as shown in Fig. 4 for permitting a nut to be received 75 therebetween and the length of the handles 11 and 12 increases the fulcrum action for firmly binding the jaws upon the nut.

The body portions 7 and 8 are provided with notches 13, formed adjacent the jaws 80 5 and 6 as illustrated in Figs. 1 and 4 these notches being adapted to be moved into registry, as shown in Fig. 4 by the moving apart of the handles 11 and 12, thus permitting a strand of wire to be inserted in 85 the notches. The handles may then be swung together as shown in Fig. 1, thus moving the notches out of registry and severing the wire strand extending therethrough, whereby these notches will perform the function 90 of a wire cutter. The plier jaw 14 has a body 15 bearing upon the handle 12 of the auxiliary jaw and it will be noted, by referring to Fig. 2 that a bolt 16 passes through the body portion 15 of the plier 95 jaw and the handle portion of the auxiliary jaw of the secondary jaw 6, thus pivotally mounting the plier jaw upon the handle of the secondary jaw. The handle 16 of the plier jaw extends beyond the body 15 thereof and contiguous to the handle 12 of the secondary jaw 6. The plier jaw 14 is provided with teeth 17 upon its inner edge, which engage the teeth 18 formed on the rear edge of the primary jaw 5, as shown 105 in Fig. 1. It is therefore obvious that the handle 15 may be urged toward the handle 11, thus bringing the teeth 17 into a binding engagement with the teeth 18, whereby an article may be gripped between the plier 110

jaw and the primary jaw, thus allowing the device to perform the functions of a plier. A hook 19 extends from the rear edge of the plier jaw 14 and extends contiguous to 5 the rear edge of the body 15, whereby the hook 19 may be used for any hooking purposes desired.

From the foregoing description it will be seen that a very simple and efficient combination wrench and plier has been produced, 10 wherein the bodies of the primary jaw and the plier jaw are pivotally mounted upon the body of the handle of the secondary jaw. Accordingly, when the handle of the secondary jaw is urged toward the handle of the primary jaw, the jaws will be swung together for gripping a nut and for actuating the wire cutter although when the handle of the secondary jaw is urged toward the handle 15 20 25 of the plier jaw, it will be seen that the body of the secondary jaw will move the primary jaw to cause the teeth thereof to engage the teeth of the plier jaw for allowing the device to be used as a pair of pliers. The foregoing description and the drawings have reference to what may be considered the preferred, or approved, form of my invention. It is to be understood that I may make such changes in construction 30 and arrangement and combination of parts materials, dimensions, et cetera, as may

prove expedient and fall within the scope of the appended claim.

Having thus fully described my invention, what I claim as new and desire to secure by Letters Patent, is:—

In a tool of the class described, the combination of a primary jaw and an auxiliary jaw having bodies extending therefrom, handles extending from said bodies, a plier jaw having a body extending therefrom and terminating in a handle, the body of said primary jaw being pivotally mounted upon the body of said auxiliary jaw, the body of said plier jaw being pivotally mounted upon the handle of the auxiliary jaw, said first mentioned handles being adapted to be moved toward each other to force said primary and auxiliary jaws toward each other, the handle of said auxiliary jaw being adapted to be urged toward the handle of the plier jaw, whereby the body of the plier jaw will move the body of the primary jaw toward the auxiliary jaw, thus causing the body of the primary jaw to engage with the auxiliary jaw.

In testimony whereof I affix my signature in presence of two witnesses.

OLE H. MELLUM.
